UNITED STATES PATENT OFFICE.

MARCUS O. ANTHONY, OF NEW YORK, N. Y., ASSIGNOR TO MORTIMER C. ROSENFELD,
OF CLEVELAND, OHIO.

GRINDING MILL.

1,402,468.

Specification of Letters Patent.

Patented Jan. 3, 1922.

Application filed February 19, 1920. Serial No. 359,970.

To all whom it may concern:

Be it known that I, MARCUS O. ANTHONY, a citizen of the United States, residing at New York, in the county of New York and 5 State of New York, have invented a certain new and useful Improvement in Grinding Mills, of which the following is a full, clear, and exact description, reference being had to the accompanying drawings.

10 This invention relates to grinding mills, and more particularly to that class of mills wherein ore is crushed between two disks, one of which is stationary and the other revolved and reciprocated in contact therewith. Some of the objects of the present invention are to provide a machine that is 15 simple in character and consisting of few parts which are inexpensive to manufacture, while further objects and advantages will 20 appear as the description proceeds.

In the accompanying drawings wherein I have shown an illustrative embodiment of my said invention, Fig. 1 is a sectional view taken on the line 1—1 of Fig. 3; Fig. 2 is 25 a rear end view of the machine; Fig. 3 is a front end view of the machine; Fig. 4 is a sectional view taken on the line 4—4 of Fig. 1; and Fig. 5 is a detail perspective view of the reciprocating mechanism.

30 Describing the various parts by reference numerals, 1 indicates a suitable base to which the fan casing 2 and the supporting table 3 are bolted. The fan casing 2 consists of a circular casting 4 provided with a discharge 35 opening 5 and hingedly mounted on the front of the casing is the door 6 carrying the stationary disk 7 and the feed hopper 8 communicating with the center of the grinding disks. The supporting table 3 may

40 be a casting provided with suitable recessed dove-tailed rails 10—10 which are supported by the legs 11 and held in spaced relationship at the top by the base member 12. On one side of the supporting table there is positioned a pair of upright cam arms or guides 45

14—14 which project upwardly above the rectangular reciprocating frame 15 which is slidably mounted on the rails 10—10 and held in contact therewith by the dove-tailed 50 members 16—16. A suitable gib 17 is placed in each dove-tailed recess to take up the wear therein. The main drive shaft 19 is journaled in suitable bearings in the support 27 and legs 11—11, and keyed thereto at the 55 inner end are the gears 20 and 22 while at

the other end there is keyed a gear 24 and a suitable drive pulley 26 which serves to revolve the shaft and gears. A hollow shaft 28 is journaled in suitable bearings in the reciprocating frame 15 and at its inner end 60 there is keyed the movable disk member 29 and adjacent thereto the gears 21 and 23 are loosely journaled on the hollow shaft and mesh with gears 20 and 22, respectively. Each of gears 21 and 23 has an extended hub 65 portion, the former having the fan 30 keyed thereon and the latter the cam 31. At the other end of the hollow shaft 28 there is keyed a gear 25 which meshes with gear 24. Adjustment of pressure between the two 70 disks is secured by means of a shaft 32 threaded into the hollow shaft 28 as indicated at 33. A hand wheel 34 serves as means to rotate the shaft and vary the pressure between the disks, and a lock nut 35 75 to hold the parts in adjusted relationship. A thrust bearing 36 takes up the end thrust of the hollow shaft 28.

In operation, power is applied to the drive pulley 26 which rotates shaft 19 and the 80 gears thereon. Gear 24 meshing with gear 25 drives the hollow shaft and rotates the grinding disk 29 in contact with disk 7. Gear 22 meshing with gear 23 rotates cam 31 between the guides 14—14 which reciprocates the frame 15 and imparts lateral movement to the disk 29, and gear 20 meshing with gear 21 rotates the fan 30. The material to be ground is fed into the hopper 8 which guides it to the inner faces of the 90 disks where it is ground to the desired size which is determined by the pressure between the two disks. As the material is ground it drops down into the fan casing where it is picked up by the current of air from the 95 fan and forced out through the opening 5.

Having thus described my invention, what I claim is:

1. In a device of the character described, the combination with a support, of a member slidably mounted on said support, a shaft journaled in said member, a grinding disk mounted on said shaft, a second disk mounted in operative relationship to said first mentioned disk, a casing surrounding 100 said disks, and means for rotating said shaft and reciprocating said member, thereby to effect a like motion between said disks.

2. In a device of the character described, the combination with a support, of a carriage 110

slidably mounted on said support, a shaft journaled in said carriage, a grinding disk mounted on said shaft and rotatable therewith, a stationary disk disposed in operative relationship to said rotary disk, a cam secured to said shaft, connections between said cam and said support whereby rotation of said shaft will reciprocate said carriage, and means for driving said shaft.

10 3. In a device of the class described, the combination with a support, of a carriage adapted to be reciprocated on said support, a

shaft journaled in said carriage, a grinding disk mounted on said shaft and rotatable therewith, a casing surrounding said disk, a 15 stationary disk mounted within said casing and disposed in operative relationship to said rotary disk, and means for driving said shaft and reciprocating said carriage, thereby to effect a similar motion between said 20 disks.

In testimony whereof, I hereunto affix my signature.

MARCUS O. ANTHONY.
